UNITED STATES PATENT OFFICE.

LOUIS ROBERTS, OF BROOKVILLE, PENNSYLVANIA.

TRUNK LOCK.

Application filed January 17, 1924. Serial No. 686,787.

To all whom it may concern:

Be it known that I, LOUIS ROBERTS, a citizen of the United States of America, residing at Brookville, in the county of Jefferson and State of Pennsylvania, have invented certain new and useful Improvements in Trunk Locks, of which the following is a specification.

This invention relates to certain new and useful improvements in trunk locks of the hasp type wherein the usual swinging snap fasteners are eliminated and positive lock devices are provided and operate in connection with the swinging hasp mechanism 10 to be controlled in their operation thereby.

A further object of the invention is to provide a trunk lock wherein a swinging locking hasp is key operated to be released with positively operating lock devices replacing 20 the usual swinging hooks or clasps with link connections between the locking clasp and swinging hasp adapted to be operated during the opening swinging movement of the hasp for releasing the several lock devices 26 retaining the trunk in a locked condition.

With the above and other objects in view that will appear as the nature of the invention is better understood, the same consists of the novel form, combination and arrangement of parts hereinafter more fully described, shown in the accompanying drawings and claimed.

In the drawings, wherein like reference characters designate corresponding parts 35 throughout the several views,

Figure 1 is a fragmentary front elevational view of a trunk equipped with the improved lock mechanism of the present invention,

Figure 2 is a vertical longitudinal sectional view taken on line II—II of Fig. 4 showing the links and bell crank devices operated by the swinging hasp for releasing the end locks of the trunk,

Figure 3 is a detail sectional view showing the hinge connections between the trunk body and cover,

Figure 4 is a horizontal sectional view taken on line IV—IV of Fig. 1 showing the 50 locking mechanism associated with the front wall of the trunk,

Figure 5 is a detail sectional view showing the swinging hasp moved to an open position for operating the end locks,

Figure 6 is a detail sectional view taken

on line VI—VI of Fig. 4 showing one of the end locks, and

Figure 7 is a fragmentary front elevational view of the lower section of the trunk body showing the keeper plate for the 60 swinging end of the hasp.

Referring more in detail to the accompanying drawings, there is illustrated a trunk lock associated with a trunk embodying a body 1 and a cover 2 hinged thereto 65 at one edge as at 3, the trunk being preferably rectangular in plan view as illustrated, although other forms may be employed.

The trunk is provided with a hasp lock, embodying a plate section 4 secured as at 70 5 to the forward side wall of the lid 2 with a hasp 6 hinged as at 7 to the lower edge of the fixed plate 4 and adapted to be swung downwardly to overlie the forward side of the trunk body 1 for cooperation with the 75 keeper plate 8 that is secured in position as at 9 upon the trunk body. The inner face of the swinging hasp 6 has a lock casing 10 secured thereto with a sliding latch bolt 11 projecting from the outer end of the lock 80 casing, the swinging hasp 6 being provided with a longitudinally extending opening having a portion thereof overlying the key hole in the lock casing 10 and normally closed by a sliding plate 12 having a finger 85 notch 13 to effect operation thereof against the spring tension thereon as shown in Fig. 5. The sliding plate 12 carries a depending lug 14 having a pin 15 attached thereto and sliding through an opening in the lug 16 90 depending from the hasp 6 with a coil spring 17 surrounding the pin 15 between the lugs 14 and 16 normally tending to hold the sliding plate 12 in a closed position overlying the key hole opening in the lock casing 10.

The keeper plate 8 as shown in Fig. 7 embodies a rectangular wall 18 projecting outwardly from the keeper plate with an inwardly directed flange 19 carried by the 100 lower end of the wall 18 for cooperation with the latch bolt 11 of the swinging hasp, the flat spring 20 disposed within the keeper plate engaging the swinging hasp to move the same outwardly when the latch bolt is 105 released.

End locks for the trunk are employed in lieu of the usual swinging clasp as shown in Figs. 1 and 4, one of the end locks being illustrated in Fig. 6 with portions of 110

the casing broken away and shown in section to illustrate the lock mechanism therein, each end lock embodying a keeper casing 21 secured as at 22 to the outer face 5 of the trunk body 1, the keeper casing 21 being open at its upper end and having projecting upwardly from the side walls thereof, inwardly extending latch lugs 23. The lock casing 24 of the end lock is secured as at 25 to the trunk cover 2 in alignment with the keeper casing 21, the lock casing 24 enclosing a pair of latch levers 26 pivotally mounted as at 27 and carrying depending latch heads 28 projecting outwardly of the lower open end of the lock casing 24 with the latch heads 28 normally separated or spring pressed outwardly by the spring 29 engaging the latch lever 26 below the pivot point thereof. When the 10 trunk lid or cover 2 is moved to a closed position as illustrated in Fig. 1, the latch heads 28 are projected into the adjacent open end of the keeper casing 21 and automatically engage the latch lugs 23 in the 15 keeper casing.

The releasing means for the latch levers 26 embodies devices associated with the swinging hasp and latch levers, a casing 30 secured as at 31 to the inner face of 20 the forward side of the trunk cover 2 aligned with the mounting plate 4 of the swinging hasp overlies an opening 32 formed in the front wall of said cover. A pair of bell crank levers 33 is pivotally supported within 25 the casing 30, the corresponding leg 34 of each bell crank lever normally traversing the wall opening 32 as shown in Fig. 2 while the other leg 35 of each bell crank lever 30 has a relatively long link connection 36 that extends through a side opening 37 in the casing 30 with the cam lever 38 pivotally mounted as at 39 within each end lock casing 24. the connection between the outer 40 ends of the links 36 and the cam levers 38 including a pin 40 slidably projected through the slotted opening 41 in the front wall of the cover section. The cam lever 38 includes a double cam portion 42 disposed between the upper ends of the 45 latch levers 26 to effect simultaneous op-

eration thereof. The swinging hasp 6 carries a finger extension 43 disposed within the mounting plate 4 when the hasp is in a closed position, the finger 43 being projected through the opening 32 in the front wall of the cover when the hasp 6 is swung upwardly as illustrated in Fig. 5 with the free end of the finger 43 engaging the legs 34 of the bell crank levers 33 for shifting the bell crank levers and links 36 for operating the cam lever 38. It will therefore be seen that when the hasp 6 is elevated after being released from the keeper plate 8, the end locks are automatically released and the trunk cover 2 may be shifted to an open position. 55

While there is herein shown and described the preferred embodiment of the present invention, it is nevertheless to be understood that minor changes may be made therein 70 without departing from the spirit and scope of the invention as claimed.

What is claimed is new is:—

1. In a trunk lock, a key-operated swinging hasp, end locks including tensioned latch levers and rigid keeper lugs for the latch levers, and means for disengaging the latch levers from the lugs arranged in the path of movement of the hasp. 75
2. In a trunk lock, a key-operated swinging hasp, end locks including tensioned latch levers and keeper lugs for the latch levers, a finger extension carried by the hasp and link and lever mechanism interposed between the latch levers and swinging hasp adapted to be operated by the finger extension on the hasp. 80
3. In a trunk lock, a swinging hasp, end locks including tensioned latch levers and keeper lugs for the latch levers, a finger extension carried by the swinging hasp, a lever-cam pivoted between the latch levers, bell-cranks pivoted adjacent the hasp and link connections between the lever-cams and bell-cranks with one leg of each bell-crank arranged in the path of movement of the hasp finger. 85 90

In testimony whereof I affix my signature.

LOUIS ROBERTS.
